(57) **CLAIM**

The ornamental design for a lock body, as shown and described.

DESCRIPTION

FIG. 1 is a top right perspective view of the lock body;
FIG. 2 is a left perspective view of the lock body of FIG. 1;
FIG. 3 is a bottom right perspective view of the lock body of FIG. 1;

FIG. 4 is a front view of the lock body of FIG. 1, the rear view being a mirror image; and,

FIG. 5 is a right side view of the lock body of FIG. 1, the left side view being a mirror image.

The broken lines represents portions of the structure that form no part of the claim.
